DESIGN FOR A MAN'S BICYCLE

Thomas I. Duffy, Detroit, Mich., assignor to The Westfield Manufacturing Company, Westfield, Mass., a corporation of Massachusetts

Application September 21, 1935, Serial No. 58,649

Term of patent 14 years

To all whom it may concern:

Be it known that I, Thomas I. Duffy, a citizen of the United States, residing at Detroit, in the county of Wayne and State of Michigan, have invented a new, original, and ornamental Design for a Man's Bicycle, of which the following is a specification, reference being had to the accompanying drawing, forming a part thereof.

Fig. 1 is a side view of a man's bicycle embodying my new design.

Fig. 2 is a plan view of the bicycle of Fig. 1.

I claim:

The ornamental design for a man's bicycle, as shown.

THOMAS I. DUFFY.
